CASE FOR A PORTABLE LAUNDRY UNIT

Harold F. Brogdon, Grand Rapids, Mich., assignor, by mesne assignments, to Automatic Music, Inc., Grand Rapids, Mich., a corporation of Delaware

Filed June 9, 1958, Ser. No. 51,271

Term of patent 3½ years

(Cl. D49—1)

FIG. 1

FIG. 2

FIG. 3

FIG. 4

Fig. 1 is a front perspective view of a case for a portable laundry unit showing my new design;

I claim:

The ornamental design for a case for a portable laundry unit, as shown.
